MACHINE FOR PRODUCING SPHERICAL SURFACES

Arthur Howard White, Stourbridge, England

Application March 21, 1956, Serial No. 572,984

Claims priority, application Great Britain March 24, 1955

11 Claims. (Cl. 51--131)

This invention is concerned with a new machine for producing spherical surfaces such, for example, as part-spherical ends or heads on rods and spindles, or part-spherical concave seatings, by any machining process such as milling, grinding, lapping or the like.

One method used at present for producing a spherical end on a rod is to use a form tool ground to the required radius and fed in a right angles to the axis of rotation of the work-piece. This method suffers from a number of obvious disadvantages. The feed must be stopped at exactly the right point from the axis of rotation or the sphere will be oblate. One tool will produce a sphere of only one diameter. The rotation of the component gives a cutting speed which varies from a maximum at the top diameter to zero at the axis. Furthermore, the truth of the sphere, even if the feed-in is correct, is dependent wholly on the accuracy of the form tool, and any imperfections in its edge will leave rings or grooves on the work. Again, if the tool is a formed grinding wheel, the load on its bearings is wholly transverse to its axis of rotation and any play in the bearings will give rise to trouble.

Another method, more generally used, overcomes some, but not all, of the disadvantages of that described above. This is to move the tool in an arc about the centre of the desired sphere whilst the work is rotated about an axis passing through that centre. However, there is still present the disadvantage of varying cutting speed, and there is now the added drawback that the tool or grinding wheel has only point contact with the work and will consequently wear rapidly. The resultant groove in the tool or wheel will then, it is true, give line contact with the work, but this will then be incorrect for any subsequent work with a different radius of curvature. If it were possible to maintain the surface of the tool truly flat, the spherical surface would present under a microscope a spiral of minute flat surfaces. As the tool-holder must move in an arcuate path, it is difficult, if not impossible, to fit at the same time a progressive inward feed.

In this second method, the accuracy of the sphere is dependent on the freedom from play of the pivot about which the tool-holder moves. Yet this pivot must be free enough to allow smooth and steady movement, as any interruption or hesitation in the travel of the tool will produce a ring or groove on the work. Where the tool is a grinding wheel, the grinding load produces opposite sideway loads, on the two bearings of the grinding spindle. All these are potential sources of vibration which give rise to errors in the truth of the sphere produced.

It is known in the glass industry to advance a rotating work-piece, such as a lens, towards a rotating grinding wheel, the axis of which makes an angle with that of the work. However, it is evident that this method cannot be used to produce surfaces of more than a hemisphere; furthermore, and this is a particularly important point, it is virtually impossible to make the surface with

2

a centre at an accurately predetermined point relative to the workpiece.

According to the present invention, a spherical surface is produced on a work-piece by rotating it about an axis 5 and advancing towards it a tool rotating about a second axis intersecting but not parallel to the first, the line of advance of the tool being along the second axis. The centre of the surface produced will be the point of intersection of the two axes and its sphericity will be virtually perfect. The tool may have a single cutting point or may be a circular edge or a cutter with a series of teeth arranged in a circle, with its centre on and its plane perpendicular to its axis of rotation.

If the surface to be produced is to include a part passing through the axis of rotation of the work-piece, as would be the case in a ball end on a rod, then the advance must stop at the point where the circular path of the tool just passes through the axis of rotation of the work-piece. Then, as the axial position of the work is 15 fixed during machining and the tool advances along a fixed line to a predetermined point, it is possible to control very accurately the size and position of the surface produced.

Where the sphere is to be ground, the tool may be a 25 hollow cylindrical grinding wheel, the inner edge of which makes contact with the work along a circle which will be termed the "grinding line." If a concave surface is to be produced, the square end of a solid cylindrical wheel is used.

It will be appreciated that the active cutting edges, 30 whether a single rotating tool, the teeth of a milling cutter, or the abrasive particles in a grinding wheel, move in a direction, which is generally transverse to the direction of movement of the surface of the work. This 35 prevents a continuous ridge or groove being formed in the work by any irregularity in the tool. Furthermore this means that, in grinding, an extremely high finish can be obtained, which is not limited by the grain size of the wheel. In fact, the finish can be many times 40 better than the grit of wheel used, a result which is unapproachable by any other method. The slower the rotation of the work relative to that of the wheel, the better the finish for a given grain size of wheel used.

In one machine according to the invention for carrying out the above method, there are provided on a bed 45 two heads bearing rotating spindles, one carrying the work and the other carrying a grinding or cutting tool. The two axes of rotation lie in a common plane and one 50 of the heads, preferably the cutting or grinding head, can be moved in an arc about an axis perpendicular to that plane, and preferably intersecting the axis of rotation of the tool spindle. The work head can be displaced horizontally in a direction perpendicular to its own axis 55 of rotation, for reasons which will become apparent later.

A stop may be provided on the work head which can 60 be swung into line with the chuck carrying the work, and enables the work to be quickly set to the right position axially. On the grinding head a diamond dressing tool 65 may be provided, swinging in a plane perpendicular to the axis of rotation of the grinding wheel, and this plane forms a fixed datum for determining the grinding line, irrespective of wear of the wheel.

The machine preferably includes means for automatically advancing the grinding head rapidly up to the work, feeding it in slowly, and then providing a dwell at the end of the stroke to give a very fine finish to the work. During the dwell of the grinding wheel, the 70 rotation of the work may be slowed right down.

The invention will now be described more fully with reference to the accompanying drawings, in which:

Figure 1 shows diagrammatically examples of the disposition of the work and wheel in the application of the invention to grinding;

Figure 2 shows a front elevation of a machine for carrying out the method of the invention;

Figure 3 is a scrap section on the line 3—3 of Figure 2;

Figure 4 shows to a larger scale a section of the work head on the line 4—4 of Figure 3;

Figure 5 shows in detail the reduction gear embodied in the headstock spindle;

Figure 6 is a scrap view of the grinding head looking from the left in Figure 1;

Figure 7 is a section to a larger scale of the upper half of the grinding spindle assembly, taken on the line 7—7 in Figure 6;

Figure 8 is a scrap sectional elevation of the grinding head and part of the associated advancing mechanism for the slide;

Figure 9 is a sectional elevation of the lower part of the grinding head, showing the feed-in mechanism; and

Figure 10 is a plan view of the feed-in mechanism within the grinding head.

Referring first to Figure 1(a), there is shown a hollow cylindrical grinding wheel 1 forming a part-spherical enlarged end 2 on a rod 3. The rod is rotated about its own axis A, and the wheel is independently rotated at a higher speed about its axis B. It will be seen that the inner edge of the end of the wheel 1 engages the surface of the sphere on a circle which we have called the grinding line, and that, since both the work and the wheel are rotating about different axes, the sphere must inevitably be true, with its centre on the intersection C of the two axes, when the wheel has been fed in along its own axis B sufficiently far for it to come into contact with the whole of the surface of the end 2. Normally, the end 2 will have previously been machined or ground roughly to a spherical shape by a form tool or wheel, and the method according to the invention will only be used to give a final truing cut.

In order to ensure that no unground portion is left on the end 2 adjacent the axis of the rod 3, it will be seen that the feed-in of the wheel 1 must end at such a point that the grinding line just intersects the axis A. This means that for a given radius of spherical surface and a given diameter of grinding wheel, the angle α between the axes of rotation of the work and of the wheel is fixed. This angle, which will be termed the setting angle, is fixed by the relationship:

$$\sin \alpha = \frac{D}{2R}$$

where D is the diameter of the inner edge of the wheel and R is the radius of the sphere to be produced.

Normally however, there is also the limitation that a particular fraction of a sphere is required, i. e. perhaps a large spherical end is required, or only a dome representing a small fraction of a sphere. The setting angle α must be at least half the angle subtended at the centre between the edge of the sphere and the axis A, which angle is called θ . A convenient rule to adopt is to make $\alpha = \frac{1}{2}\theta + 5^\circ$, which gives the cutting edge of the wheel a reasonable arc of travel clear of the work, to prevent its clogging. For example, in Figure 1, in which the end 2 is slightly less than a hemisphere, θ is 80° , making $\alpha = 45^\circ$. In these circumstances, as α is fixed by the shape of the head, the required value of D is determined from α and R.

For adjustment of the setting angle, the axis B of the grinding wheel 1 can be turned about a focal point F. Now if this point F were to be made coincident with C, the intersection of the axes, then to cater for large radii one would require a large wheel, and furthermore, unless the head holding the work is to be made movable axially, then on a machine catering for reasonably large

radii the overhang with small radius work would be impossibly great. Instead, the point F is fixed, and the axis A can be offset laterally from it. This also enables the distance K from the plane of the grinding line to the point F to be fixed independently of the work which, as will be seen, makes it possible to determine extremely accurately the point at which the feed-in of the wheel stops and hence the final diameter of the work. The offset of the axis A from F is indicated at O and 10 is given by the relationship:

$$O = K \sin \alpha - \frac{D}{2} \cos \alpha$$

Figure 1(b) shows the set-up for grinding a ball head 15 large in comparison with the diameter of the rod, and in Figure 1(c) is shown the grinding of a dome of large radius. It will be seen that the off-set O is negative. Figure 1(d) shows an example of the formation of a spherically-backed mushroom end on a rod.

In Figures 1(e) and (f) are shown two examples of the grinding of concave spherical surfaces by the method according to the invention. The relationships are exactly the same as before, but the wheel is of course a plain cylindrical one with an outside edge used as the cutting edge.

Whilst in Figure 1 we have shown throughout a grinding wheel 1, it will be understood that it may equally well be replaced by a milling cutter, or even by a single tool rotating about the axis B. If a single tool is used, however, the rotation of the work must be very slow in comparison to that of the tool if a reasonable finish is to be obtained, and the job would take a correspondingly long time.

An example of a practical machine for carrying out the invention, and embodying a number of refinements, is shown in the remainder of the drawings. Referring to Figure 2, the machine comprises a bed 10, on which is mounted a headstock 11 for rotating the work and a table 12 on which the grinding head is mounted.

The headstock 11 is mounted on transverse slides, one V and one flat, on the bed 10, so that it can be moved horizontally in a direction transverse to the axis of the headstock spindle 13 (Figure 3), on the end of which is a collet chuck 14 for carrying the work. The transverse position of the headstock is controlled by a lead screw actuated by a handle 15, which has a micrometer scale (not shown) and enables the "offset" O of the axis of rotation of the work (i. e. the headstock spindle) from the focal point to be controlled very accurately. A lever 16 serves to open and close the chuck 14.

The bed 10 has its upper surface formed as a quadrant at 17, and the table 12 is pivoted on a spigot projecting vertically upwards from the centre of the quadrant; the axis of the spigot if extended upwards, would pass near the collet chuck, and its point of intersection with the horizontal plane of the headstock spindle 13 represents the focal point F of Figure 1. An arcuate rack or gear segment 18 on the bed 10 is engaged by a pinion 19 on the underside of the table 12, this pinion being driven through gearing from a handwheel 20. This enables adjustment of the setting angle against a micrometer scale to within 15 seconds of arc. Once the angle has been set, the table is locked in position by clamps, so that it is rigid with the base during actual grinding.

The actual grinding spindle 21 is formed by an integral extension of the shaft of an electric motor built into a housing 22 on a slide 23. This slide 23 is mounted on slideways of generous dimensions on the table 12, so as to be movable towards and away from the focal point. The grinding spindle is in exactly the same horizontal plane as the work spindle 13 and its axis passes through the focal point F (i. e. the intersection with that plane of the vertical axis about which the table 12 can be turned).

The headstock 11 carries a stop 25 on the end of an arm 26 pivoted on a spindle 27. A handle 28 enables the stop to be swung down in front of the chuck 14 and it may be provided with a micrometer screw to enable it to be moved in the direction of the axis of the headstock spindle. This stop enables the work to be set rapidly in the correct axial position with respect to the focal point F, due allowance being made for the amount to be ground off.

The interior of the headstock 11 is shown in Figures 4 and 5. At 29 and 30 respectively are the V and flat slides on which it is carried on the base. It will be seen that the lever 16 is secured to a shaft 31 carrying lugs 32 on which pins engage an annular groove in a sleeve 33 rotating with the headstock spindle 13, to control the axial position of the sleeve. This sleeve 33 has a conical surface engaging a pair of pivoted bell-crank levers 34, which in their turn engage the end of a tube 35 running coaxially within the spindle 13 and acting on a split sleeve 36 containing the jaws 37 of the collet chuck. It will be understood that angular movement of the lever 16 opens and closes the jaws of the chuck. The work, of which a typical example is shown at 38, is held in the jaws 37 by means of a split bush 39, which enables the shank of the work to be gripped even though there is a ball head on each end. An axially sliding plunger 40 within the sleeve 36 is urged outwards by a coil spring 41 and tends to push the work outwards. This simplifies setting the axial position of the work, as it is clamped in the chuck whilst being urged gently against the stop 25, which is then swung out of the way.

The spindle 13 runs in opposed conical bearings 42 and 43, and carries, keyed to it, a spider 44 (Figure 5) the fingers of which extend between balls 45 forming an epicyclic reduction gear between a sun wheel in the form of a V pulley 46 and an annulus 47 formed with a V pulley groove 48. Both the sun and annulus are free to turn on the spindle 13 and the engaging pressure is derived from angularly spaced coil springs 49, the thrust being taken by a ball race 50.

The pulleys 46 and 47 are connected by belts 51 and 52 respectively to separate electric motors contained in the base 10. During normal grinding the right-hand pulley 48 is stationary and only the left-hand pulley 46 is driven, so that the spindle 13 is driven at a lower speed through the reduction gear formed by the balls 45. When a very low rotational speed of the spindle is required, during the dwell as will be described later, the second motor is started up to drive the annulus 47 in the opposite direction but at a slightly lower speed than the pulley 46, and only the difference in speeds is transmitted to the balls 45.

Turning now to the grinding head, Figures 6 and 7 show the upper part of the housing 22, in which is mounted an electric motor 55, its shaft 56 being mounted in special bearings lubricated by oil mist from a special pressure lubricator which has been indicated at 57 in Figure 2 but has been omitted from the remainder of the drawings for clarity. This enables the shaft 56 to run up to speeds as high as 24,000 R. P. M.

On the end of the shaft 56 there is screwed a boss 58 carrying a cup-shaped grinding wheel 59. A bracket 60 carries a transparent guard 61 to protect the operator from coolant flung off the wheel.

As mentioned earlier, the housing 22 and slide 23 are movable with respect to the table 12 in the direction of the axis of the grinding spindle. There are two separate mechanisms for effecting the inward movement, one for providing a rapid advance up to the work and a finer one for producing a slow feed-in during the actual grinding operation. The first of these mechanisms is shown in Figure 8 and comprises an air cylinder 62 under the control of a solenoid-operated valve actuated from a push button on the bed 10. The cylinder itself is pivoted to the table 12 and its movable piston advances a link

63 to tilt a motion plate 64, forming a toggle linkage with a further link 65 pivoted at 66 to the slide 23, thus advancing the slide rapidly and taking the wheel 59 to within a few thousandths of an inch of the work. Figure 9 shows the linkage in the fully advanced position.

The pivot 67 about which the plate 64 turns is substantially stationary during the rapid advancing motion described above, but is not mounted directly on the table 12. On the contrary, it is carried on the top end of a lever 68, of which the upper arm is only one fifth of the length of the lower arm. The second of the mechanisms referred to above, for giving a slow progressive feed-in, is connected via a link 69 to the lower end of the lever 68 and comprises a slide 70 movable on a sub-assembly 71 within the table 12 and urged to the right in Figure 9 by a compressed air cylinder 72. The rate of movement is controlled by an oil dashpot 73, the piston of which is connected to a piston rod 74 screwed into the slide 70. The flow of oil from one side of the piston to the other takes place through pipes 75 leading to a metering valve 76 (shown more clearly in Figure 10), which can be readily adjusted by hand.

Referring now to Figure 10, a link 77 pivotally mounted at one end on the subassembly 71 forms at its other end a pivot for a lever 78, which is itself pivoted at its mid-point to the top of the slide 70. At its free end the lever 78 carries a striker plate 79, which is kept with its face square to the line of movement of the slide by means of a member 80 forming a parallel linkage with the lever 78. It will be seen that the five-to-one magnification of the lever 68 combined with the two-to-one ratio of the lever 78 gives a linear movement of the striker plate 79 which is ten times that of the slide 23.

A carriage 81 is mounted for sliding movement on the sub-assembly 71 in a direction parallel with that of the movement of the slide 70. Its position is adjusted by means of a lead screw 82 under the control of a hand wheel 83 which is provided with a micrometer dial 84 (Figure 9). A stop formed by an electric micro-switch 85 is mounted rigidly on top of the carriage 81 in the path of the striker plate 79 and a second micro-switch 86 on a carrier 87 is mounted for sliding movement on the carriage. A splined shaft 88 actuated by a knob 89 with a micrometer setting dial 90 enables the position of the switch 86 to be altered with respect to the carriage 81 irrespective of the overall position of the carriage. Adjustable bolts 91 below the micro-switches form positive dead stops to bring the striker plate 79 to a halt immediately after the corresponding micro-switch has been actuated.

As stated earlier, operation of a push button on the base 10 opens a solenoid-controlled valve to admit air to the cylinders 62 and 72. This is effected through a pipe 92. The quick advance produced by the cylinder 62 is continued as a slow feed-in by the cylinder 72 until the striker plate 79 engages the micro-switch 86, initiating the action of an electronic timer which, after a predetermined time delay, admits air to a pipe 93 connected to the exhaust sides of the cylinders to actuate them in a reverse direction until the plate 79 engages the stop 91 and the other micro-switch 85. The micro-switch 85 is in series with the starting button and prevents the next cycle of operations being started by the operator unless the slide 23 is fully retracted.

A T-junction 94 in the pipe 93 branches off to an air cylinder 95, which applies air pressure to the fluid in the hydraulic circuit of the dashpot 73 to prevent cavitation behind the piston on the reversal of direction.

It will be seen that the total distance of the slow feed-in is controlled by the knob 89, which fixes the distance apart of the two micro-switches. The feed-in may be varied over a range from one thousandth up to one quarter of an inch. Once the overall feed-in has been set (this depends on the amount of material to be removed), the wheel 83 is used to set the points at which it starts

and ends in relation to the focal point. This is determined by the requirement that the front face of the wheel 59 at the end of the stroke should be the distance K of Figure 1 from the focal point F.

A diamond dressing tool 96 is carried on an arm 97 pivoted to a carrier 98 (Figures 2 and 3) on the table 12 to move in an arc in a vertical plane under the influence of a control handle 99. The diamond is traversed across the face of the wheel 59 with the slide 23 in its fully retracted position.

The final forward position of the wheel, i. e. its position during the dwell, should be such that the face of the wheel is the fixed distance K from the focal point F. If there were no slow feed-in, this would simply be fixed by the foremost position of the rapid advance, but, with the additional slow feed-in, this final position will be forward of the foremost position of the rapid advance by an amount equal to the slow feed-in. Now the amount of the feed-in is variable (under the control of the knob 89), so if this is to end at the right point, the diamond 23 must dress the wheel to a plane which is behind the rearmost position of the rapid advance by an amount equal to the slow feed-in which has been set.

This may be achieved by an adjustable anvil or stop (not shown) which can be attached to the arm 97 of the diamond dresser. The stop fixes a plane which is separated from the focal point by a distance equal to K plus the total rapid advance. It includes a micrometer screw which enables the plane of the diamond to be set by a predetermined amount beyond that plane (in a direction away from the focal point) which distance is made equal to the feed-in set by the knob 89. Then, provided the knob 89 is not disturbed, this serves as a datum for all subsequent operations on the particular batch of work being ground, as, when the grinding wheel 59 wears, the wheel 81 is turned by the operator to advance the carriage 81 a few thousandths of an inch and the wheel is trimmed by the diamond in the fully retracted position. Then, on the next feed-in the wheel stops with its newly dressed face at exactly the plane at which the previous face stopped before.

The length of time of the feed-in and of the dwell will depend upon the size, material and centre angle of the sphere to be ground, also on the grade and grit of the wheel and the amount of material left on the work-piece for removal.

During the dwell the speed of rotation of the work may be brought right down. In one example the work is rotated at 25 R. P. M. during the feed-in and then at only 4 R. P. M. during a dwell of about one minute. By this means it has been found possible to achieve an extremely high surface finish, of as little as one and a half micro-inches, which is better than could be achieved by ordinary lapping. This is chiefly attributable to the fact that the direction of movement of the cutting edges on the tool (in this case the abrasive particles in the grinding wheel) is substantially transverse to that of the surface of the work itself.

It will be appreciated that the load on the bearings of the grinding spindle is wholly axial, so that there is no tendency for sideways play to develop. It should also be noted that the truth of the sphere is not affected by any error in the concentricity of the collet chuck, since the centre of the sphere will always lie on the axis of rotation of the work, irrespective of the position of the axis of the work itself.

To overcome difficulties in getting coolant to penetrate inside the cup grinding wheel, the wheel may be of a special impregnated self-lubricating kind. The machine described may also be used for lapping, and has the advantage that the spherical form of the work is not destroyed during the course of the lapping operation.

I claim:

1. Apparatus for producing a spherical surface on a work-piece comprising a first rotatable spindle, means on

said first spindle for retaining a work-piece, a second rotatable spindle, cutting means carried on said second spindle, said cutting means being displaced from the axis of said second spindle and defining a circular path about said axis, said first and second spindles lying in a common plane, means for causing relative angular movement between said spindles about an axis perpendicular to said plane, means for advancing said second spindle along its own axis of rotation up to the point where said circular path intersects the axis of rotation of said first spindle.

2. Apparatus for producing a spherical surface on a work-piece comprising a bed, a headstock on said bed, a first rotatable spindle, said first spindle being mounted for rotation about a horizontal axis in said headstock, work-holding means on said first spindle, a table, said table being mounted on said bed for angular movement about a vertical axis, a slide on said table, said slide being reciprocable horizontally in a direction passing through said vertical axis, a second rotatable spindle, said second spindle being mounted for rotation on said slide about a horizontal axis intersecting said vertical axis, a cutting tool mounted on said second spindle and defining in its rotation a circular path, means for causing rotation of said first and second spindles and means for advancing said slide on said table in a direction towards said vertical axis.

3. Apparatus according to claim 2, wherein said headstock is adjustable on said bed in a horizontal direction perpendicular to the axis of rotation of said first spindle.

4. Apparatus according to claim 2, wherein said means for causing rotation of said first spindle comprises an electric motor driving through an epicyclic reduction gear having an input sun wheel, an annulus, and a planet cage, said first spindle being connected to said planet cage, and including means for driving said annulus in a direction opposite to that of said sun wheel.

5. Apparatus according to claim 2, wherein said means for advancing the slide comprises a first means for producing a rapid advance, in conjunction with a second means for producing an additional slow feed-in.

6. A machine for producing a spherical surface on a work-piece comprising a bed, a headstock, and a table, said headstock being mounted for sliding horizontal movement on said bed and said table being mounted on said bed for angular movement about a vertical axis, a work-carrying spindle mounted for rotation about a horizontal axis in said headstock perpendicular to the direction of sliding of said headstock on the bed, a first electric motor, means for driving said work-carrying spindle from said first motor, a slide mounted for sliding movement on said table in a horizontal direction passing through said vertical axis, an electric motor on said slide having a spindle, the axis of rotation of said motor spindle being horizontal, parallel with the direction of movement of said slide, and intersecting said vertical axis, a grinding wheel on said motor spindle, said grinding wheel defining a circular path of contact with the work, means for advancing said slide rapidly towards said vertical axis, further means for advancing said slide slowly, and means for stopping the advance at the point where said circular path intersects the axis of said work-carrying spindle.

7. A machine according to claim 6, wherein said means for stopping the advance of the slide is adjustable in position.

8. A machine for producing a spherical surface on a work-piece comprising a bed, a headstock mounted on said bed, a work-carrying spindle mounted for rotation in said headstock, power means for driving said work-carrying spindle, a table mounted on said bed, a pivotal connection between said table and bed, a slide mounted on said table, a grinding spindle mounted for rotation in said slide, power means for driving said grinding spindle, said spindles having their axes intersecting and lying in a common plane, the axis of said pivotal con-

nection intersecting that of said grinding spindle, and being furthermore perpendicular to said common plane, means for clamping said pivotal connection, a grinding wheel carried on said grinding spindle, said grinding wheel having a plane end face and a cylindrical surface, the intersection of said face and surface defining a line herein termed the "grinding line," means for advancing said slide with respect to said table in a direction parallel with the axis of rotation of said grinding spindle, and means for halting its advance at the point where said grinding line intersects the axis of rotation of said work-carrying spindle.

9. A machine as claimed in claim 8, including a diamond dresser, said diamond dresser being mounted on said slide for movement in a plane which is perpendicular to the axis of said grinding spindle and is a fixed distance from the axis of said pivotal connection. 15

10. A machine as claimed in claim 8, wherein said

means for advancing said slide comprise a first pneumatic motor on said table, a toggle linkage, pivotal connections between said motor and linkage and between said linkage and said slide, a second pneumatic motor on said table, 5 and a lever interconnecting said second motor and said toggle linkage.

11. A machine as claimed in claim 8 wherein the axes of said work-carrying and grinding spindles lie in a horizontal plane and the axis of said pivotal connection is vertical. 10
